UNITED STATES PATENT OFFICE.

MAX GINSBURG, OF PHILADELPHIA, PENNSYLVANIA.

INTERCHANGEABLE LETTER-EMBOSSING DIE.

No. 921,974.

Specification of Letters Patent.

Patented May 18, 1909.

Application filed June 1, 1908. Serial No. 435,887.

To all whom it may concern:

Be it known that I, MAX GINSBURG, a citizen of the United States, residing at Philadelphia, in the county of Philadelphia and State of Pennsylvania, have invented certain new and useful Improvements in Interchangeable Letter-Embossing Dies, of which the following is a specification.

My invention relates to embossing mechanism, and particularly to a mechanism for embossing and forming sheet metal signs, the object of my invention being to provide embossing dies having interchangeable elements capable of being quickly removed, changed or transposed, thus allowing the various letters or character units forming the die for one sign, to be quickly changed and reset-up to form a die for embossing another sign.

To this end my invention consists in the arrangement of parts and detail of construction as shown in the accompanying drawings and set forth in the appended claims.

In the drawings Figure 1, is a perspective view of one half of my die. Fig. 2, is a transverse section on the line $x-x$ of Fig. 1. Fig. 3, is a perspective view of the other half of the die with the spacing blocks removed in order to more clearly show the construction. Fig. 4, is a transverse section on the line $z-z$ of Fig. 3. Figs. 5 and 6, are perspective views of the male and female units respectively, and Fig. 7, is a perspective of a corner of one of the inner frames. Fig. 8, is a perspective view of one of the small spacing blocks.

Like reference characters throughout the several views designate like parts.

A designates an exterior frame or chase within which is mounted an interior letter carrying frame B. Both of these frames are shown as square in plan, though they obviously may be made of any other rectangular figure. There are two of these chases, one for the male and the other for the female die.

The frame A is adapted to be placed in and attached to any suitable embossing press, and it is provided on its sides with the set screws A', having heads a' and the nuts a², the shanks of the set screws passing through the sides of the frame and provided inside the frame with the nuts a² whereby the set screws may be clamped and held in any suitable position. It will be seen from Figs. 2 and 4, that the frames are each provided with a solid bottom plate A².

The frame B is smaller than the frame A, has no bottom plate, and is adapted to be set within the frame A. The set screws A' will engage with the sides of this frame, and by adjusting the set screws relatively to each other the internal frame B may be adjusted to its proper central position with reference to the frame or chase A and be rigidly held therein. The frames B are alike for both the male and female dies and hence the description of one will apply quite as correctly to the other.

The frame B is formed of two side pieces b and two end pieces b', the side pieces b project over the end pieces b' in order to form the joint at the corners of the frame, and the end pieces b' are provided at their extremities with die portions b² whereby an ornamental corner will be made at the corner of the frame. Both the side and end pieces are formed with a marginal flange b³, in the frame forming part of the female die which fits down over the outside of the male die frame.

It is of course, to be understood that the frame forming the male die is provided with projections at the corners of the frame, and the female die with recesses as shown in Figs. 1 and 3. I have shown the face of the side and end pieces plain, but it is to be understood that they may be made of any ornamental character desired, so as to impress an ornamental border around the margin of the sheet metal sign made thereby.

In order to support the spacing blocks and letter blocks within the frame B, I provide the transverse wires D which pass through a series of perforations d' in the side frames b and project out on both sides of the frame. These wires are of a strong and rigid character and carry on their ends, the wing nuts and washers d. There may be as many of these wires as desired, but they should be evenly spaced apart. I have found by practice that a distance of one inch is a convenient spacing distance for these wires.

The end pieces b' are also formed with passages or perforations d' and the wires D may be strung between the end pieces b' in place of between the side pieces b. These rods not only act to support the letter and spacing blocks as hereafter described, but they also act to hold the sides and ends of the frame B tightly together. It will be understood of course, that I may use any further means of joining rigidly the sides and end pieces and in this connection I prefer to use the dowels E

in the end pieces entering the dowel opening *e* in the side pieces as shown in Fig. 7.

The letter blocks *F*, and spacing blocks *F'*, *F''*, *F'''* are formed of any desired size and 5 are rectangular in plan, so that the several blocks shall fit closely together when mounted within the frame *B*. Each block has passages *f* through it, these passages being the same distance apart as are the wires *D*.

10 In the large letter blocks *F* as shown in Fig. 3, there will be two or three passages *f* passing transversely through them, while longitudinally there will be at least two passages in the larger blocks. These passages 15 are preferably an inch apart and I prefer to use this unit through my construction. The blocks are multiples of each other, so that they shall fit together as shown in Fig. 1, several small blocks occupying the place of one 20 large block if desired.

I preferably use three sizes of blocks, the largest *F*, *F'*, being the letter blocks and the large spacing blocks, the next size *F''* acting as fillers, and the smaller size *F'''* which are 25 preferably one inch square being used around the margins of the frame. These blocks however, may be placed in any position desired in order to fill up the space within the frame and hold the letter blocks rigidly in position, so that they cannot slip from one side to the other, and so that a smooth background will be formed for the die.

While I have shown the letter blocks as being of the largest size, I of course do not wish 35 to limit myself in this regard as I may also use smaller blocks for the subordinate lettering. It will of course be understood that the letter blocks on the male die have the letters raised thereon, and that on the female die the 40 letters are correspondingly depressed.

By providing the blocks with passages *f* running in opposite directions I am enabled to set the letter blocks in any position desired within the chase. The construction 45 enables the removal of any of these blocks and the substitution of others, or permits rearranging the blocks in any desired manner by simply unscrewing the nuts on the rods *D*, removing the blocks and replacing them 50 with others, of course changing the spacing blocks to correspond. The nuts are then replaced upon the rods *D*, the form is locked and placed within the chase *A* and locked in place therein by the marginal set screws *A'*.

55 It will be seen that when locked in place the blocks are backed by the bottom or top plates *A²* of the male or female chase, that they are rigidly held against any lateral movement, not only by the tension of the wires *D* 60 but by the spacing blocks, and that the wires

D hold the blocks in position, positively preventing them from being shifted or falling out of the chase.

In operation a sheet of metal of suitable thickness is placed between the male and female members of the die which are held in any suitable embossing press and the members pressed together whereupon the sheet metal is embossed according to the letters or other elements supported within the frame. 65 70

While I intend my device to be particularly used for embossing lettered signs, it may also be used for more ornamental signs wherein the units or elements *F*, *F'*, *F''* may be of an ornamental character entirely. Of 75 course, I may use these ornamental units in conjunction with the letter units and the spacing units before described. By means of my invention I am enabled to set up the embossing units of sheet metal signs very 80 quickly and to impress these signs at short notice and in a manner which has been impossible heretofore.

Having thus described my invention what I claim as new and desire to secure by Letters Patent is:

1. An embossing die including a frame formed of side and end pieces provided with a series of transverse wires having tightening means on their ends, and embossing units 90 and spacing blocks shiftably mounted upon said wires and removable therefrom.

2. An embossing die including male and female die frames, each frame composed of side and end pieces, said frames being formed 95 on their faces with male and female embossing projections and recesses, a series of wires passing across said frames having nuts on opposite ends of each wire whereby the sections of the frame may be held rigidly together, and letter blocks having passages through which the wires pass, said blocks having male and female faces, spacing blocks also formed with passages for said wires and adapted to be placed around the said die 100 blocks, and a chase into which said die carrying frame is set, said chase having a backing against which the die units are supported, and means on the margins of the chase for locking the chase in place, and adjusting the 105 frame and the chase with relation to each other.

In testimony whereof I have singed my name to this specification in the presence of two subscribing witnesses.

MAX GINSBURG.
